UNITED STATES PATENT OFFICE.

TORVAL J. ANDERSON, OF ROCKDALE, WISCONSIN.

FOOT-LEVER.

1,157,140.

Specification of Letters Patent.

Patented Oct. 19, 1915.

Application filed December 7, 1914. Serial No. 875,951.

To all whom it may concern:

Be it known that I, TORVAL J. ANDERSON, a citizen of the United States, residing at Rockdale, in the county of Dane and State 5 of Wisconsin, have invented certain new and useful Improvements in Foot-Levers, of which the following is a specification.

This invention relates to foot levers or pedals employed for operating the brakes 10 and clutches of motor vehicles, and its object is to provide a novel and improved lever of this kind which can be lengthened or shortened, and also adjusted forward or backward to properly position the same on 15 the car.

The clutch and brake pedals of an automobile are usually mounted in a fixed position, and are thus frequently so located that they are not readily accessible to some 20 drivers. However, by making the pedal adjustable it may be set so as to be within easy reach of the driver's foot.

The herein stated object is attained by means of a combination and arrangement 25 of parts to be hereinafter described and claimed, reference being had to the accompanying drawing in which—

Figure 1 is a side elevation of the device; Fig. 2 is a front elevation thereof; Fig. 3 is 30 an enlarged section on the line 3—3 of Fig. 1; Fig. 4 is a sectional detail on the line 4—4 of Fig. 3; Fig. 5 is an enlarged section on the line 5—5 of Fig. 2, and Fig. 6 is a section on the line 6—6 of Fig. 5.

Referring specifically to the drawing, the 35 foot lever or pedal is composed of two adjustably connected sections, the same being indicated at 10 and 11, respectively, the former having a foot plate 12, and the latter 40 being suitably connected to the clutch or other part to be controlled, which need not be illustrated as it forms no part of the present invention. That end of the section 11 to which the section 10 is connected has a 45 sector-shaped enlargement 13 and said section 10 is forked to straddle the part 13, the fork branches being indicated at 14.

The sections 10 and 11 are pivotally connected by means of a bolt having an intermediate portion 15 which is non-circular in cross-section and seats in a correspondingly shaped hole 16 in the section 11, whereby said bolt is held against rotation. Any other suitable means may be provided for non- 55 rotatably connecting the bolt to the section 11. On each side of the part 15, the shank

of the bolt is oblong, the oblong portions being indicated at 17, one of which has a head 18 and the other being threaded to receive a nut 19. The fork branches 14 are slotted 60 longitudinally, as indicated at 20, the bolt ends 17 extending into said slots. At one end of the slots is an enlargement 21 corresponding to the part 15 of the bolt, in order that the same may be seated in the hole 16. 65 The other ends of the slots also have enlargements 22, and the slots also have intermediate enlargements 23. The width of the slots corresponds to the width of the minor dimension of the portions 17 of the bolt, 70 whereas the enlarged portions 22 and 23 correspond to the major dimension of the portions 17 of the bolt. Thus, the section 10 can be swung about the bolt when the latter coincides with the enlarged slot portions 75 22 and 23, but to effect the adjustment of the section 10 lengthwise with respect to the section 11, the former must first be swung to place the slots in line with the minor dimension of the bolt portions 17. The section 80 can then be shifted to locate the bolt in any one of the enlarged portions of the slots, and after the desired enlarged portion is reached, the section 10 is swung so that the major dimension of the bolt parts 17 85 extend transversely of the slots, which prevents further longitudinal movement of the section 10. The section 10 is fixed in adjusted position by tightening the nut 19, 90 the same being opposite the outer face of one of the fork branches 14, whereas the bolt head 18 engages the outer face of the other fork branch.

The connection between the sections 10 and 11 also allows the former to be set at 95 various angles with respect to the latter, and in order to lock the section 10 after it is set at the desired angle, a spring latch is provided, the same comprising a pin 24 carried by a spring tongue 25 at one end of the latter, the other end of said spring tongue being secured by the nut 19. The fork branches 14 have longitudinally spaced apertures 26 to receive the latch pin, and in the part 13 of the section 11 are apertures 100 27 through any one of which the latch pin also passes. The apertures 27 are arranged in a curve having for its center the pivot bolt connecting the sections 10 and 11. The number of apertures 26 corresponds to the 110 number of positions the section 10 may be adjusted lengthwise as hereinbefore de-

scribed. The drawing shows the section 10 capable of two adjustments, but this may be varied by providing the slots 20 with additional intermediate enlargements, and the 5 fork branches with a corresponding number of additional apertures 26. Upon retracting the latch pin 24, the section 10 may be adjusted angularly with respect to the section 11, and upon replacing the pin, the section 10 is securely locked in said adjusted 10 position.

In order to prevent the operative connection between the sections 10 and 11 being broken if the latch pin 24 should be accidentally disengaged, the part 13 has safety 15 stop shoulders or abutments 28 at one end which will intercept the fork branches 14 and thus transmit to the section 11 the motion of the section 10 in a direction to control the clutch or other part to which the section is connected. The foot plate 12 is also adjustable as to length, the same having 20 a heel extension piece 29. Thus, the foot plate is composed of two sections, and 25 as the same are adjustably connected, they may be set to suit the foot of the driver. The adjustment between the sections is effected by forming the section 29 with a longitudinal slot 30, through which pass bolts 31 carried by the section 12. Nuts 32 30 screwed on the bolts hold the sections in adjusted position. The edges of the slot 30 are recessed at intervals, as indicated at 33, to form enlargements of the slot and seats 35 for the bolts, the shanks of the latter being flattened, so that they are elongated in cross-section. The width of the slot corresponds to the width of the minor dimension of the bolt shank, whereas the enlarged portions of 40 the slot correspond to the major dimension of the bolt shank. Thus, before the foot plate section 29 can be adjusted relative to the section 12, it is necessary to turn the 45 bolts in the enlarged portions of the slot and bring the minor dimensions of the bolts in line with the slot. The section 29 may then be shifted until the bolts reach the desired enlarged portions of the slot, and then by giving the bolts a quarter turn so that 50 their major dimensions extend transversely of the slot, and tightening the nuts 32, the parts are securely held in adjusted position. The bolt heads may be countersunk in the top of the section 12. The section 29 has 55 a rear marginal heel engaging flange 34, and the section 12 has side flanges 35 between which the driver's foot seats.

While the invention is primarily designed for clutch and brake pedals of automobiles, 60 it is not limited thereto, and it may be used in connection with other mechanism. Various changes and modifications in the structural details shown and described may also be made without a departure from the spirit 65 and scope of the invention.

I claim:

1. A lever comprising sections which are pivotally connected to permit angular adjustment, and a bolt passing transversely through the sections to provide the pivotal 70 connection therebetween, one of the sections being slotted longitudinally, through which slot the pivot bolt passes to permit longitudinal adjustment of the sections, and means for locking the sections in adjusted 75 position.

2. A lever comprising sections, one of which is adjustable lengthwise and angularly with respect to the other, means for locking the sections in adjusted position, 80 and a safety stop for the first-mentioned section, operable on failure of the locking means.

3. A lever comprising sections, one of which is adjustable lengthwise and angularly with respect to the other, means for locking the sections in adjusted position, 85 and a safety stop on the second-mentioned section in the path of the first-mentioned section.

4. A lever comprising sections, one of which is forked to straddle the other section, the fork branches being slotted longitudinally, and portions of the slots being enlarged, a pivot bolt carried by the other 90 section and having ends which are oblong in cross-section and extend into the aforesaid slots, the minor dimensions of the oblong portions of the bolt corresponding to the width of the slots and the major dimensions of said bolt portions corresponding to the enlarged portions of the slots, and a latch pin carried by the first-mentioned section, the fork branches having longitudinally spaced apertures, and the second-mentioned section having a curved series of apertures for the latch pin. 100

5. A lever comprising sections, one of which is forked to straddle the other section, the fork branches being slotted longitudinally, and portions of the slots being enlarged, a pivot bolt carried by the other section and having ends which are oblong 110 in cross-section and extend into the aforesaid slots, the minor dimensions of the oblong portions of the bolt corresponding to the width of the slots and the major dimensions of said bolt portions corresponding to the enlarged portions of the slots, a nut screwed on the bolt, a latch pin, and a spring 115 tongue carrying the latch pin, said spring tongue being secured to one of the fork branches by the aforesaid bolt, the fork branches having longitudinally spaced apertures, and the second-mentioned section having a curved series of apertures for the latch pin. 120

6. A lever comprising sections, one of which is forked to straddle the other section, the fork branches being slotted longitudi- 125 130

nally, and portions of the slots being enlarged, a pivot bolt carried by the other section and having ends which are oblong in cross-section and extend into the afore-
5 said slots, the minor dimensions of the oblong portions of the bolt corresponding to the width of the slots and the major dimensions of said bolt portions corresponding to the enlarged portions of the slots, a latch
10 pin carried by the first-mentioned section, the fork branches having longitudinally spaced apertures, and the second-mentioned section having a curved series of apertures for the latch pin, and a safety stop on the second-mentioned section in the path of the 15 fork branches.

In testimony whereof I affix my signature in presence of two witnesses.
